DESIGN FOR A CARTON FOR PAPER TOILET SEAT COVERS

Warren W. Dunnell, Los Angeles, Calif.

Application November 13, 1944, Serial No. 116,299

Term of patent 14 years

(Cl. D58—12)

To all whom it may concern:

Be it known that I, Warren W. Dunnell, a citizen of the United States, residing in the city of Los Angeles, county of Los Angeles, and State of California, have invented a new, original, and ornamental Design for a Carton for Paper Toilet Seat Covers, of which the following is a specification, reference being had to the accompanying drawing, forming part thereof, in which:

Fig. 1 is a front view in elevation of a carton for paper toilet seat covers showing my new design.

Fig. 2 is an elevation of each end of the carton;

Fig. 3 is a rear elevation;

Fig. 4 is a top plan view;

Fig. 5 is a bottom plan view.

I claim:

The ornamental design for a carton for paper toilet seat covers, as shown.

WARREN W. DUNNELL.
